(57) **CLAIM**

The ornamental design for a heel for a shoe, as shown and described in the drawings.

DESCRIPTION

FIG. 1 is a back perspective view of a heel for a shoe showing my new design;

FIG. 2 is a back elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken line showing of a heel for a shoe is included for the purpose of illustrating only and forms no part of the claimed design.

1 Claim, 5 Drawing Sheets
